PORTABLE BROILER AND COOKER COMBINATION

Peter L. Helgeson, Macungie, Pa., assignor to Caloric Corporation, Topton, Pa., a corporation of Pennsylvania

Filed May 23, 1966, Ser. No. 2,383

Term of patent 14 years

(Cl. D81—10)

FIG. 1 is a perspective view of a portable broiler and cooker combination embodying the design.

FIG. 2 is an elevational view of the end of the portable broiler and cooker opposite to that shown in FIG. 1.

FIG. 3 is a top plan of FIG. 1.

FIG. 4 is an elevation of the side of the portable broiler and cooker combination which is not visible in FIG. 1.

FIG. 5 is a bottom plan of FIG. 1.

What I claim is:

The ornamental design for a portable broiler and cooker combination, as shown.
